CLAIM

The ornamental design for a pet grooming comb as shown and described.

DESCRIPTION

FIG. 1 is a left front perspective view of a pet grooming comb showing my new design;

FIG. 2 is a left rear perspective view thereof;

FIG. 3 is a left side elevational view thereof, the right side elevational view being a mirror image thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left front perspective view of the second embodiment of a pet grooming comb, showing my new design.

FIG. 9 is a left rear perspective view thereof;

FIG. 10 is a left side elevational view thereof, the right side elevational view being a mirror image thereof;

FIG. 11 is a front elevational view thereof;

FIG. 12 is a rear elevational view thereof;

FIG. 13 is a top plan view thereof; and,

FIG. 14 is a bottom plan view thereof.

The solid black surface shading represents the color black.

1 Claim, 10 Drawing Sheets
